AROMA V. THOMPSON, OF MOSCOW, IDAHO.

HOOK AND EYE.

1,281,710.

Specification of Letters Patent. Patented Oct. 15, 1918.

Application filed November 27, 1916, Serial No. 133,780. Renewed March 19, 1918. Serial No. 223,464.

To all whom it may concern:

Be it known that I, AROMA V. THOMPSON, a citizen of the United States, residing at Moscow, in the county of Latah and State of Idaho, have invented certain new and useful Improvements in Hooks and Eyes, of which the following is a specification.

This invention relates to certain new and useful improvements in hooks and eyes and has for its primary object, the provision of a device of this character in which the hook and eye will be of such construction that each may be securely fastened to the clothing at their opposite corners or ends in such manner as to prevent slipping of the hook and eye.

Another object of the invention resides in the provision of a hook and eye of the above stated character which will be of improved and simplified construction and in which the hook will have several engaging portions for contact with the straight main portion of the eye bar.

A further object resides in the provision of a device of the above stated character which will be of such construction that the hooks will automatically lock upon the straight portion or bar of the eye thereby prevent disengagement of these members except when the proper pressure is applied to the same to force separation of the hook and eye.

With the above and other objects in view, as will be apparent as the description proceeds, the invention consists in the novel combination and arrangement of parts as will be hereinafter more specifically set forth, pointed out in the appended claims and shown in the accompanying drawings.

In the accompanying drawings forming a part of this application and in which like designating reference characters refer to corresponding parts throughout the several views,

Figure 1 is an enlarged perspective view of the improved form of hook and eye, and

Fig. 2 is a longitudinal sectional view through the same secured to overlapping portions of an article of clothing and engaged with one another to secure together the closure flaps, parts of my improved hook and eye being shown in elevation.

Referring more in detail to the drawings, 1 designates the main portion of the eye or eye bar, as it will be hereinafter referred to and which is provided with the eyes 2 at its

opposite end to be secured to a closure flap in any suitable and well known manner. The eye bar 1 is offset outwardly from the eyes 2 and thereby spaced from the closure flap. It will also be understood that the eyes 2 are formed by bending the offset ends or extremities of the eye bar 1. The closure flap to which the eye is secured, is designated by the numeral 3 in Fig. 2, while the overlapping or remaining flap is designated by the numeral 4.

The hook is composed of a single strip of wire or the like having its opposite ends 5 extended in parallel relation with portions 6 offset to form locking portions of the hook, the purpose of which will later appear. The locking portions are adjacent the free extremities 7 of the wire, as will be readily understood by referring to the drawings. After being extended for a suitable distance to form the inner portions of the long legs of the hook, the ends 5 of the wire are bent upon themselves and turned back to form the securing eyes 8 of the hook, at the free extremities of the long legs of the same. The wire is then extended parallel to the ends 5, as shown at 9, to form the outer sides of the long legs and after being extended for a short distance past the free extremities 7 of the wire, the ends of the wire are again turned as shown at 10, the legs being turned this time at a right angle to the turns 8, however, to provide the outer or end engaging portions of the hook, which portions 10 bear against the eye bar 1 when the hook and eye are in locked engagement. After the turns 10 are made, the ends of the wire are extended back beneath the outer side portions of the long legs, to form the outer side portions 11 of the lower or short legs of the hook. At the opposite ends of the short legs, the ends of the wire are again turned as shown at 12, with said turned portions 12 extended at a right angle to the turned portions 10 and in a plane corresponding to the plane of the turned portions 8. The turned portions 12 form the inner rounded ends of the short legs of the hook and from said inner ends or free ends of the short legs, the ends of the wire are again extended forwardly, parallel to the outer sides 11 of said short legs to form the inner sides 13 of said short legs, after which said ends of the wire are curved upwardly, as shown at 14 to connect with the inwardly turned central portion 15 of the wire. The turned portions 14

form the inner eye bar engaging portions of the hook.

The outer sides 11 and inner sides 13 of the short legs of the hook are spaced apart 5 sufficiently to receive the locking portions 6 of the hook or at least permit the same to extend into the short legs should pressure be applied to the hook and eye, which would tend to force said locking portions 6 toward 10 the short legs. The locking portions 6 may, however, normally rest in a slightly spaced position from the short legs but close enough to the same to prevent the eye bar 1 from being accidentally disengaged from the 15 hook. It is also to be understood that the locking portions 6 may be readily forced away from the short legs of the hook to permit the eye bar 1 to pass between said locking portions 6 and the short legs when the 20 proper pressure is applied to either engage or disengage the hook and eye. It will be clear that as the eye bar 1 is secured by its opposite ends to one closure flap and the hook is secured to the remaining or overlapping 25 closure flap at the turned and spaced portion 8 and the hook engages the eye bar 1 at the four points indicated by the numerals 10 and 14, twisting or slipping of the hook and eye with respect to one another 30 will be practically eliminated.

While the form of the invention shown and described is what is believed to be the preferred embodiment thereof it is nevertheless to be understood that minor changes 35 therein in the details of construction and arrangement of parts may be resorted to within the scope of the appended claims, without departing from the spirit of the invention.

40 I claim:—

1. A garment fastener formed from a length of wire bent to provide spaced parallel loops adapted to lie against a garment, and for engagement with an eye, the extremities of the length being arranged in 45 parallel relation and extended reversely to

afford attaching loops, the extreme extremities of the reverse portions constituting keepers to normally lie above the spaced parallel loops to prevent the disengagement 50 of the eye member from the spaced parallel loops.

2. A garment fastener formed from a length of wire having its end portions extended in parallel relation and extended 55 reversely to provide keepers, the intermediate portions of the wire being bent to provide spaced parallel loops, the loops being connected by longitudinal curved substantially U-shaped medial portion and above 60 the parallel loops.

3. A garment fastener formed from a length of resilient wire bent to provide parallel legs and reversely extended, the extremities of the reversely extended legs being 65 longitudinally curved to provide keepers, substantially parallel loops formed with each of the legs and disposed below the keepers, and a substantially U-shaped longitudinally curved portion connecting the 70 loops, said keepers being normally engaged with the garment.

4. A garment fastener formed from a length of material bent to provide outer legs and reversely extended, the extremities of 75 the reversely extended legs constituting keepers, substantially parallel loops formed with each of the legs and disposed at one side of the keepers, and a medial curved portion connecting the loops, each of said 80 keepers being disposed upon the opposite sides of the curved medial portion and adjacent the parallel legs, said parallel legs limiting the movement of the keepers in one direction.

85 In testimony whereof I affix my signature in presence of two witnesses.

AROMA V. THOMPSON.
